United States Patent Office

Des. 182,313
Patented Mar. 11, 1958

182,313

PANEL OF PLASTIC SHEET MATERIAL OR SIMILAR ARTICLE

Arthur D. Sylvester and Arno H. Scheiding, Rowayton,
Conn., assignors to L. E. Carpenter & Company, Inc.,
Wharton, N. J., a corporation of New Jersey

Application February 25, 1957, Serial No. 44,964

Term of patent 14 years

(Cl. D87—3)

Fig. 1.

Fig. 2.

Fig. 1 is a plan view of a full panel of plastic sheet material embodying our new design;

Fig. 2 is a vertical sectional view, taken along line II—II of Fig. 1; and

Fig. 3 is a sectional view taken along line III—III of Fig. 1.

We claim:

The ornamental design for a panel of plastic sheet material or similar article, substantially as shown.
